CLAIM

The ornamental design for a neck light as shown and described.

DESCRIPTION

FIG. 1 is a perspective view of the neck light showing our new design;

FIG. 2 is a front elevational view thereof;

FIG. 3 is a back elevational view thereof;

FIG. 4 is a right side elevational view thereof;

FIG. 5 is a left elevational view thereof;

FIG. 6 is a top plan view thereof; and,

FIG. 7 is a bottom plan view thereof.

The broken lines illustrate portions of the neck light that form no part of the claimed design.

1 Claim, 4 Drawing Sheets
